UNITED STATES PATENT OFFICE.

GEORGE W. MAY, OF AKRON, OHIO.

HORSESHOE FOR PITCHING CONTESTS.

Application filed November 9, 1921. Serial No. 513,879.

To all whom it may concern:

Be it known that I, GEORGE W. MAY, a citizen of the United States, residing at Akron, in the county of Summit and State of Ohio, have invented certain new and useful Improvements in Horseshoes for Pitching Contests, of which the following is a specification.

This invention relates to the game or art of pitching horse-shoes, the practice of which game is familiar to many, and which has of recent years attained a considerable and increasing popularity. Of late, the art of pitching horse-shoes has been given considerable study by those who are expert and has been developed into a scientific pursuit, in which many experts are now engaged. As a horse-shoe is an irregularly shaped body generally elliptical and open at one point, and as it is usually provided with calks or the like, its action as a projectile in passing through the air is the compound of many forces acting in different directions. The landing of the shoe at the stake and its position of rest are also factors which enter into the contest, the object being to place the shoe in such position on the stake that it cannot be dislodged, by the opponent, and if possible to cause the shoe to land in such position that it will block the stake for the opponent.

Horse-shoe pitching contests are played in expert or championship games, with stakes slightly inclined at a distance of forty feet, the ground or court around the stake being usually a soft clay.

I have given the art of horse-shoe pitching considerable time and study and it is the purpose of the present invention to so construct a shoe that its flight through the air can be easily and accurately governed and so that its position at the stake will be as advantageous as possible.

These and other objects will appear as the description proceeds, it being understood that, except as such matters are material to the invention, I am not confined to details or dimensions and proportions herein described.

In the drawings:

Fig. 1 is a plan view of the horse-shoe of my invention. 50

Fig. 2 is an elevation of the toe of the shoe. 55

Fig. 3 is a section on the line 3—3 of Fig. 1. 60

Fig. 4 is a section on the line 4—4 of Fig. 1. 65

Fig. 5 is an elevation of one of the open ends of a shoe. 70

The shoe is so formed that it is evenly balanced throughout, the center of gravity being located slightly forward of the actual or geometrical center point. 75

From the opening at the rear or heel, the shoe is formed with straight inwardly diverging portions 2, which extend to about the point 3, as indicated by the line F, a distance slightly more than one-fourth of the total length of the shoe. In horse-shoes formerly used for pitching purposes, the ends of the shoe customarily curved inwardly from the heel or point. As a result of this construction, when the shoe is thrown toward the stake, should the side of the shoe near the opening strike the stake, a spinning action is set up which tends to throw the shoe away from the stake. All expert horse-shoe pitchers strive to throw the shoe with a fixed turning movement and to make the shoe land with the opening toward the stake, the shoe striking the ground with sufficient velocity to cause it to slide forward until the inside of the toe of the shoe is at the stake. 80

With my construction, if the inside of the shoe strikes against the stake a short distance in, the tendency for the shoe to spin will not arise, but the shoe will go straight in toward the stake. 85

The inner and outer surfaces of the shoe are formed on curves of gradually decreasing radius until it reaches the smallest radius A at the toe. The successive radii are noted by the letters B, C, D and E. As a result of this construction there is formed at the toe of the shoe a pocket or sharp concavity and as the shoe passes into the stake it will tend to rest at about the center of the toe against 90

the inner edge of the shoe. This makes an ideal location for the shoe and one from which it is hard to dislodge the shoe.

It will be noted that the breadth of the arms of the shoe gradually increases as they approach the toe, thus, for example merely, it is preferred to make the shoe at the tip or open end approximately $1\frac{1}{2}$ inch; at the point marked X it is increased to about $1\frac{1}{8}$ inches, and at the point X it is approximately $1\frac{5}{8}$ inches which width is maintained to the toe. These dimensions are by way of example merely and illustrate the gradually increasing breadth of the arms of the shoe, which in combination with the carks to be described later, places the center of gravity of the shoe at about the center A. This places the center of gravity of the shoe at such a point that its flight through the air can be more easily controlled, the heavy toe end causing the toe cark to bury itself firmly in the ground.

On the toe portion of the shoe is formed the cark 4. In prior horseshoe constructions this cark is formed in a straight line or as a chord across the toe of the shoe, and has usually been set back from the edge of the shoe a slight distance. In my present construction the cark is rounded and is placed at the outer edge of the shoe so that as shown in Fig. 3 the front edge of the shoe 5 is formed in a straight line at a slight backward taper, flush with the outer surface of the shoe. The rear edge of the cark 6 is tapered at a slightly greater angle.

Several valuable results are obtained by this construction. In pitching shoes it is the aim of the player to throw the first shoe as a ringer, and to throw the second shoe also as a ringer, if possible, or to lock the first shoe so that it cannot be knocked away by his opponent. The curved or arc shaped cark of the present shoe will often drop down or rest within the curve on the inside of the first shoe firmly locking itself and the other shoe in position. With the former straight cark at the toe portion, the cark on the second shoe would often span the curvature on the first and could be easily knocked away.

The tapering surfaces of the cark causes the shoe to bury itself deeply in the clay of the court. By placing the cark so that its outer surface is continuous or flush with the outer surface of the shoe, should the shoe strike the court on edge, it will not bury itself in the ground in upright or inclined position, as with former constructions, but will fall to the ground. This action of the shoe will often mean a ringer which would be lost if the shoe stood up in the ground.

The carks 7 at the heel or open end of the shoe are formed in much the same manner as the toe cark for similar reasons.

In perfecting the shoe in the manner described it has been my purpose to correct some of the faults which have developed from the use of ordinary horse-shoes, or former shoes manufactured solely for pitching purposes. I have made an extensive study of the art of shoe pitching and believe that I have produced a shoe for this purpose which involves new principles and actions of the shoe both as a projectile and in landing at the stake. I believe that I am the first to design a shoe with these points in mind and am entitled to a broad range of equivalents and to liberal scope in the consideration of the attached claims.

Claims:

1. A horseshoe for pitching purposes, the arms of which converge to an unobstructed opening at the heel portion of the shoe, the inner surfaces of the arms being formed as straight lines diverging from the opening and extending to points between one-third and one-fourth of the total length of the shoe, thereupon merging with a curved line extending over the remainder of the shoe, whereby, should the shoe strike the stake against its inner surface, a spinning action will be set up only after the shoe has passed the stake between one-third and one-fourth of its total length.

2. A horse-shoe for pitching purposes, the arms of which taper gradually from the toe portion of the shoe to the open ends or heel portion, and provided with a cark located on the toe portion of the shoe so as to place the center of gravity of the shoe on the toe side of the geometrical center.

3. A horseshoe for pitching purposes, said shoe being provided with an integral elongated arc-shaped cark at the toe and with carks extending across the two heels, said carks being placed flush with the outer edge of the shoe at the toe and with the ends of the heel portions respectively, the shoe being so designed and proportioned that the center of gravity of the shoe is on the toe side of its geometrical center.

4. A horseshoe for pitching purposes, the arms of which taper gradually from the toe portion of the shoe to the open ends or heel portion, and provided with an elongated cark at the center of the toe portion and with carks extending across the two heels, said heel carks being placed flush with the ends of the arms.

5. In a horseshoe for pitching contests, the combination of a solid, substantially flat bar curved in the shape of a horseshoe said bar tapering toward the heel of the shoe to place the center of gravity on the toe side of the geometrical center of the shoe, the open ends of the shoe being formed on their inner surfaces with two straight lines

from the opening of the shoe to a point between one-third and one-fourth of the total length of the shoe whereupon they merge with a curved line over the balance of the 5 inner surface of the shoe, heel calks at the extremities of the open end of the shoe said calks extending transversely over the en-

tire width of the bar and tapered outwardly thereof, and a toe calk which is arc-shaped and placed at the outer circumference of the 10 shoe and is of a width approximately one-half of the width of the bar and is tapered outwardly thereof.

GEORGE W. MAY.
